VERTICAL LIFT CARGO PLANE

Lincoln B. Wiley, Hawthorne, Calif., assignor to Doak Aircraft Co., Torrance, Calif., a corporation of California

Filed Sept. 14, 1959, Ser. No. 57,539

Term of patent 14 years

(Cl. D71—1)

FIG. 1.

FIG. 2.

FIG. 3.

Fig. 1 is a top plan view of a vertical lift cargo plane showing my new design;

Fig. 2 is a side elevational view thereof, the opposite side being substantially the same in appearance; and

Fig. 3 is a front elevational view thereof.

The bottom of the plane of my design is substantially similar to the top plan view shown in Fig. 1.

I claim:

The ornamental design for a vertical lift cargo plane, as shown and described.
